Primary Examiner — Holly E Thurman*Assistant Examiner* — Kristopher Michael Blechschmidt(74) *Attorney, Agent, or Firm* — NOLTE LACKENBACH SIEGEL; N. Alexander Nolte(57) **CLAIM**

The ornamental design for a mount as shown and described.

DESCRIPTION

FIG. 1 is a front top perspective view of a mount of my invention.

FIG. 2 is a bottom rear perspective view of FIG. 1.

FIG. 3 is a top plan view of FIG. 1.

FIG. 4 is a bottom plan view of FIG. 1.

FIG. 5 is a right side elevation view of FIG. 1.

FIG. 6 is a left side elevation view of FIG. 1.

FIG. 7 is a front side elevation view of FIG. 1; and,

FIG. 8 is a rear side elevation view of FIG. 1.

The dash-dash broken lines in the drawings illustrate portions of the mount that form no part of the claimed design.

1 Claim, 5 Drawing Sheets(56)
